A. L. STEINKE

STOCK TANK HEATER

Filed March 15, 1923

FIG. 2.

Witness

H. Woodward

By *A. L. Steinke*
Attorneys

UNITED STATES PATENT OFFICE.

ALBERT L. STEINKE, OF PIPESTONE, MINNESOTA.

STOCK-TANK HEATER.

Application filed March 15, 1923. Serial No. 625,819.

To all whom it may concern:

Be it known that I, ALBERT L. STEINKE, a citizen of the United States, residing at Pipestone, in the county of Pipestone and 5 State of Minnesota, have invented certain new and useful Improvements in Stock-Tank Heaters; and I do declare the following to be a full, clear, and exact description of the invention, such as will enable 10 others skilled in the art to which it appertains to make and use the same.

My invention has for its object to provide a simply constructed and inexpensive, yet a highly efficient and desirable heater 15 for stock and like tanks, which will be extremely economical with fuel.

With the foregoing in view, the invention resides in the novel subject matter hereinafter described and claimed, the description 20 being supplemented by the accompanying drawing.

Figure 1 is a vertical sectional view of a tank heater constructed in accordance with my invention.

25 Figure 2 is a horizontal sectional view as indicated by line 2—2 of Fig. 1.

Figure 3 is a horizontal sectional view on line 3—3 of Fig. 1.

In the drawing above briefly described, 30 the numeral 1 designates a substantially flat rectangular casing which is divided by spaced longitudinal partitions 2, into a tortuous heat passage 3, said partitions 2 being extended inwardly from the opposite 35 end walls of the casing and each terminating in spaced relation with the wall opposite that to which it is secured. A heat outlet pipe 4, preferably formed of two sections, rises rigidly from the tank 1 and communicates 40 with one end of the heat passage 3, the upper end of said pipe being provided with an appropriate water shedding hood 5.

An air inlet 6 rises rigidly from the casing 1 and communicates with the end of the passage 3, opposite the pipe 4. The upper end of the pipe 6 is surrounded by a sleeve 7 which extends above said pipe and terminates in a horizontal plane, said sleeve 50 being held in spaced relation with the pipe, by a zig-zag metal strip 8 whose reaches

contact at their ends with said sleeve and pipe. Radial tie-bolts 9 pass through the sleeve 7, strip 8 and pipe 6 to rigidly secure these parts together. 55

An oil supply tank 10 rests on the upper edge of the sleeve 7 and forms a closure to prevent rain water, snow and the like from entering through the pipe 6, the lower end of said tank being provided with an 60 annular depending flange 11 which frictionally surrounds the sleeve 7 and thus secures the tank in place. This tank is formed in its lower end with an oil drip outlet 12 controlled by an appropriate 65 needle valve 13 which may be entirely closed when the supply of oil is to be cut off. When the valve is in this position, the tank may be removed and carried to any desired point for refilling with oil. 70

When using the device, it is submerged in a tank of water and held down by a suitable weight. Then, by removing the tank 10, a quantity of wood ashes or the like may be dropped through the pipe 6 75 into the casing, as indicated at 14. Sufficient oil is allowed to drip upon the ashes or other absorbent material and then a lighted match is dropped down the pipe 6 to ignite the oil. By now replacing the 80 tank and properly regulating the valve 13, the flame may be fed with any desired quantity of oil.

From the foregoing, taken in connection with the accompanying drawing, it will be 85 seen that an extremely simple and inexpensive tank heater has been provided, yet that it will be highly efficient and in every way desirable. As excellent results are obtainable from the details disclosed, these 90 details may well be followed. However, within the scope of the invention as claimed, numerous minor changes may be made.

I claim:

1. A tank heater having an upstanding 95 air inlet pipe, a circular open-ended sleeve surrounding and spaced from the upper end of said pipe, said sleeve extending above said pipe and terminating in a horizontal plane, means rigidly mounting said sleeve 100 on said pipe, an oil tank resting on said sleeve and having a valved drip outlet dis-

charging into said pipe, and an annular flange on the lower end of said tank frictionally engaging said sleeve to hold the tank in place.

10 extend between and contact with the pipe and sleeve, and tie-bolts passing through

- 5 2. A structure as specified in claim 1; said mounting means for said sleeve comprising a zig-zag metal strip whose reaches

In testimony whereof I have hereunto affixed my signature.

ALBERT L. STEINKE.
